COMBINED SHOWER CURTAIN AND FRAME THEREFOR

Neal H. Kellogg, Woodland, Calif., assignor of one-half to William C. Burger, Woodland, Calif.

Application April 12, 1954, Serial No. 29,956

Term of patent 14 years

(Cl. D4—3)

Fig. 1

Fig. 2

Fig. 4

Fig. 1 is a perspective view of a combined shower curtain and frame therefor embodying my new design.

Fig. 2 is an enlarged but foreshortened transverse section taken on line 2—2 of Fig. 1.

Fig. 3 is an enlarged fragmentary sectional plan view on line 3—3 of Fig. 1.

Fig. 4 is an enlarged fragmentary sectional plan view taken on line 4—4 of Fig. 1.

The bathroom and bathroom fixtures shown by means of broken lines are disclosed only for illustrative purposes.

I claim:

The ornamental design for a combined shower curtain and frame therefor, as shown and described.
